his Attorney.

UNITED STATES PATENT OFFICE.

CHARLES NEBLETT, OF CINCINNATI, OHIO.

HASP-LOCK.

SPECIFICATION forming part of Letters Patent No. 314,147, dated March 17, 1885.

Application filed May 5, 1884. (No model.)

To all whom it may concern:

Be it known that I, CHARLES NEBLETT, a citizen of the United States, residing at Cincinnati, in the county of Hamilton and State of 5 Ohio, have invented certain new and useful Improvements in Hasp-Locks, of which the following is a specification.

My invention relates to an improvement in hasps or latches, which will be fully herein-10 after described.

In the accompanying drawings, Figure 1 is a sectional perspective view of a door and frame, showing my improvement attached thereto. Fig. 2 is a transverse section of the 15 door and frame, showing the hasp in plan thereon. Fig. 3 is a detail perspective view of the hasp-catch.

A represents the door or gate upon which the hasp is secured.

20 B represents the door frame or post to which the catch is attached.

C represents the lock-bar or hasp proper, pivotally secured at one end to the door by a bolt, c. Instead of using the bolt c, a staple, rivet, or other fastening means may be employed, as customary. The free end C' of bar 25 C is bent outwardly and provided with a hole or eye, E.

D represents the catch, which the free end 30 of the hasp-bar C engages. Catch D is composed of a fastening-plate and an upturned

keeper plate or arm, preferably made integral therewith. The fastening-plate is provided with countersunk holes to receive the attaching-screws.

35 e are notches or openings in the keeper-plate, to afford access to the fastening-screws for turning them into place.

D' represents an outwardly-turned tongue on the keeper-plate, of like configuration to 40 the end C' of the hasp-bar, and provided with a similar eye, E'. When the door is closed and the hasp-bar dropped into locking engagement with the catch, the outwardly-turned tongues C' and D' lie in intimate contact, with 45 their eyes E E' in line, so that the bow f of a padlock, F, (shown in dotted lines,) or other fastening device may be inserted. The bar C, when it is locked in the catch D, covers the screws, thus preventing a removal of the catch 50 without opening the lock.

I claim—

A hasp or latch composed of a pivotal bar, 55 C, having an outwardly-turned end, C' E, in combination with a catch, D, having a keeper-plate and tongue, D' E', the said parts constructed and adapted to engage each other substantially as herein set forth.

CHARLES NEBLETT.
